UNITED STATES PATENT OFFICE.

ARCHIBALD BANNATYNE, OF WATERBURY, CONNECTICUT, ASSIGNOR TO
THE WATERBURY CLOCK COMPANY, OF SAME PLACE.

CLOCK-BELL.

SPECIFICATION forming part of Letters Patent No. 600,705, dated March 15, 1898.

Application filed September 18, 1895. Serial No. 562,882. (No model.)

To all whom it may concern:

Be it known that I, ARCHIBALD BANNATYNE, of Waterbury, in the county of New Haven and State of Connecticut, have invented a new 5 Improvement in Rear-Winding Clocks; and I do hereby declare the following, when taken in connection with the accompanying drawings and the letters of reference marked thereon, to be a full, clear, and exact description of 10 the same, and which said drawings constitute part of this specification, and represent, in—

Figure 1, a partial view, in vertical central section, of a clock containing my invention; Fig. 2, a view thereof in rear elevation; Figs. 15 3 and 4, partial views, in vertical central section, showing other ways of attaching the clock-bell to the rear movement-plate of the time-movement of the clock.

My invention relates to an improvement in 20 clocks having small cylindrical cases and provided with bells, the object being to produce a simple, cheap, and effective clock of neat appearance and constructed with particular reference to locating a relatively large bell to 25 the rear of the clock-case and providing for winding and setting the clock and performing other kindred operations by means of arbors projecting rearward through the back of the 30 clock-case and reached by means of key-openings formed in the body portion of the bell itself.

With these ends in view my invention consists in a clock having certain details of construction and combinations of parts, as will be 35 hereinafter described, and pointed out in the claims.

In carrying out my invention, as shown in Figs. 1 and 2, I employ a relatively large circular bell having a body portion A and an 40 integral circular flange A', extending inwardly therefrom at a right angle thereto. By constructing the bell with such a flange, the inner surface of which is struck by the bell-hammer, which is not shown, the bell remains 45 substantially unimpaired in tone, even though key-openings are formed in its body portion. As herein shown, the inner portion of the body portion of the bell is constructed with a key-opening A² for the insertion of a key 50 for winding the time-spring, with a key-opening A³ for the insertion of a key for winding

the alarm-spring, with a key-opening A⁴ for the insertion of a key for setting the alarm mechanism, and with a key-opening A⁵ for the insertion of a key for regulating the alarm 55 mechanism. The said key-openings A², A³, A⁴, and A⁵ are arranged in line with the winding, setting, and regulating arbors, which are not shown. The number and position of the key-openings in the bell will of course depend 60 upon the construction of the time-movement employed and the character of the clock. The said bell is nearly as large in diameter as and arranged concentric with the circular clock-case B, which may be of any approved construction and which is provided with a removable circular back B', which may also be of any approved construction and secured in place in any approved manner. The edge of the flange A' of the bell comes quite close to 70 the outer face of the back B'. For the reason that the bell is of relatively large diameter as compared with the size of the case a powerful bell, and hence a strong alarm, is secured for a clock of comparatively small size. The 75 clock-movement located within the case may be of any approved construction; but however constructed the bell will be connected with the rear movement-plate C.

In the construction shown by Figs. 1 and 2 80 I employ a heavy hub D, which is secured to and projects rearwardly from the said rear movement-plate C through a central opening B², formed in the back B' of the case, and through an opening A⁶, formed in the center 85 of the body portion of the bell, the central portion of the bell being struck inwardly to form a recess around the said opening A⁶. The extreme rear end of the hub D is reduced in diameter and exteriorly threaded for the 90 application of a retaining-nut E, which bears against the bell and holds the same against the shoulder D', formed near the outer end of the hub by reducing the rear end of the same, as set forth. The said hub is constructed with a central longitudinal opening D² for the insertion of a hand-setting key, which is applied to the squared rear end of the center or time-setting arbor F of the clock-movement, the said end of the said arbor extending rearward into the opening D² of the hub. I do not, however, limit myself to the 95 100

use of a hub for connecting the bell with the rear movement-plate of the time-movement, for the bell may be otherwise connected with the rear movement-plate. Thus in Fig. 3 the 5 bell G is secured to the rear movement-plate H by means of two posts I I, which extend rearward through the back J of the case J'. In this construction an opening G' is formed in the center of the bell for access to the 10 squared rear end of the center arbor K. In the construction shown by Fig. 4 a stirrup-like frame L is employed for securing the bell M to the rear movement-plate N, the inner ends of the said stirrup passing through 15 the back O of the cylindrical case O'. In this construction an opening M' is formed in the center of the bell and an opening L' in the outer portion of the stirrup for the access of a hand-setting key to the center arbor of 20 the time-movement.

In the constructions shown by Figs. 3 and 4 the openings formed in the body of the bell for the insertion of keys for winding the time and alarm springs and setting and regulating 25 the alarm are not shown; but it will be understood that the bells are formed with such openings as are required for access to the winding and setting arbors of the movement.

In view of the modifications suggested and 30 of others which may obviously be made I would have it understood that I do not limit myself to the exact construction herein shown, but hold myself at liberty to make such changes as fairly fall within the spirit and 35 scope of my invention.

Having fully described my invention, what I claim as new, and desire to secure by Letters Patent, is—

1. In a rear-winding clock, the combination 40 with a case having a back, of a movement-frame located within the said case, a bell arranged concentrically with and at the rear of the said back of the case, and having its central or body portion formed with one or more 45 key-openings, and means connected with the rear plate of the movement-frame and extending through the said back of the case and into the interior of the bell for connecting the same with the said rear plate of the movement-frame, whereby a relatively large bell 50 may be located at the back of the case and access had to the winding arbor or arbors of the clock-movement through the central or body portion of the bell itself, and whereby 55 also the bell is supported by the movement-frame by means located within the case and bell.

2. In a rear-winding clock, the combination with a case having a back, of a movement-frame located within the said case, a bell arranged concentrically with and at the rear of the back of the said case, and having one or more key-openings formed in its central or body portion, and a hub-like post passing through the back of the case, secured by its 60 inner end to the said movement-frame, having the said bell secured to its outer end, forming a bearing for the rear end of the center arbor of the clock-movement, and provided with a longitudinal passage through which access is had to the said arbor for setting the 65 clock.

3. In a rear-winding clock, the combination with a cylindrical case having a back, of a movement-frame located within the said case, 70 a bell arranged concentrically with and at the rear of the back of the said case and having one or more key-openings formed in its central or body portion the center of which is set inward to form a clearance-recess, a hub-like 75 post passing through the said back, secured at its inner end to the rear plate of the movement-frame, forming a bearing for the inner end of the center arbor of the clock-movement provided with a longitudinal passage for 80 access to the rear end of the said arbor for turning the same in setting the clock, and having the said bell mounted upon its outer end, which extends into the bottom of the 85 said central recess of the bell, and a nut located in the bottom of the said recess and screwed upon the projecting outer end of the hub which is thereto threaded, the nut serving to secure the bell to the hub.

4. In a rear-winding clock, the combination 90 with a cylindrical case, of an independently-formed disk-shaped back, a movement-frame located within the case, a bell arranged concentrically with and at the back of the said case, and having one or more key-openings 95 formed in it, and means for connecting the bell through the said disk-shaped back with the said clock-movement, whereby a relatively large bell may be located at the back of a cylindrical rear-winding clock, and access had to the winding arbor or arbors of the 100 clock-movement through the bell itself.

In testimony whereof I have signed this specification in the presence of two subscribing witnesses.

ARCHIBALD BANNATYNE.
